UNITED STATES PATENT OFFICE

CHARLES W. STRONG, OF SEATTLE, WASHINGTON

DESIGN FOR A GOLF SERVICE STANDARD

Application filed June 9, 1931. Serial No. 40,140. Term of patent 14 years.

To all whom it may concern:

Be it known that I, CHARLES W. STRONG, a citizen of the United States, residing at Seattle, in the county of King and State of Washington, have invented a certain new, original, and ornamental Design for a Golf Service Standard, of which the following is a specification:

Fig. 2 is a front elevation of the same.

Fig. 3 is the other side elevation of the same.

I claim:

The ornamental design for a golf service standard as shown.

In witness whereof I hereunto subscribe my name this 3d day of June, 1931.

CHARLES W. STRONG.
